United States Patent Office

Des. 183,837
Patented Nov. 4, 1958

183,837

WATER SLED OR THE LIKE

Lauren E. Hammond, Jonesville, Mich.

Application February 3, 1958, Serial No. 49,477

Term of patent 14 years

(Cl. D71—1)

Fig. 1 is a perspective view of a water sled or the like embodying my new design;

Fig. 2 is a side elevation thereof;

Fig. 3 is a front elevation thereof; and

Fig. 4 is a rear elevation thereof.

I claim:

The ornamental design for a water sled or the like, substantially as shown and described.
